US0D1053307S

(12) **United States Design Patent** (10) **Patent No.:** **US D1,053,307 S**
(45) **Date of Patent:** **** Dec. 3, 2024**

(54) **CLEANING NOZZLE FOR A WASHING MACHINE FOR MACHINED PARTS**

(71) Applicant: **SUGINO MACHINE LIMITED**, Uozu (JP)

(72) Inventors: **Koji Sugita**, Uozu (JP); **Kodai Nakazaki**, Uozu (JP)

(73) Assignee: **SUGINO MACHINE LIMITED**, Namerikawa (JP)

(**) Term: **15 Years**

(21) Appl. No.: **35/517,969**

(22) Filed: **Aug. 3, 2022**

(80) **Hague Agreement Data**

Int. Filing Date: **Aug. 3, 2022**

Int. Reg. No.: **DM/224642**

Int. Reg. Date: **Aug. 3, 2022**

Int. Reg. Pub. Date: **Aug. 4, 2023**

(30) **Foreign Application Priority Data**

Apr. 4, 2022 (JP) ..... 2022-007301 D

(57) **CLAIM**

The ornamental design for a cleaning nozzle for a washing machine for machined parts as shown and described.

DESCRIPTION

1.1 : Perspective

1.2 : Perspective

1.3 : Front

1.4 : Top

1.5 : Left

1.6 : Right

The back view is omitted because it is a mirror image of the front view; the bottom view is omitted because it is identical with the top view; the parts shown by means of broken lines in the reproductions are not part of the claimed design; the dash-dotted lines in the reproductions represent the unclaimed boundaries; the parallel thin lines in the reproductions represent contours only and do not illustrate an ornamentation or decoration on the surface of the product.

1 Claim, 6 Drawing Sheets
